(57) CLAIM

An ornamental design for a wallet, as shown and described.

DESCRIPTION

FIG. 1 is a perspective view of my wallet.

FIG. 2 is a front view thereof.

FIG. 3 is a back view thereof.

FIG. 4 is a first side view thereof.

FIG. 5 is a second side view thereof.

FIG. 6 is a top view thereof; and,

FIG. 7 is a bottom view thereof.

The broken lines represent boundaries of the claimed design and form no part of the claimed design.
